UNITED STATES PATENT OFFICE.

AUGUSTUS S. VAN HOUTEN, OF NEWARK, NEW JERSEY.

ARTIFICIAL DENTURE.

Application filed December 1, 1923. Serial No. 678,013.

To all whom it may concern:

Be it known that I, AUGUSTUS S. VAN HOUTEN, a citizen of the United States of America, residing at Newark, in the county of Essex and State of New Jersey, have invented certain new and useful Improvements in Artificial Dentures, of which the following is a specification.

My invention relates to the construction of attachments for fastening removable dentures to natural teeth.

Some of the objects of my invention are: first, the construction of an efficient connection between a bridge, plate or similar device containing artificial teeth and a clasp or other removable means of attachment to a natural tooth; second, to join an artificial denture with a natural tooth in such manner that the denture may be readily and completely removed from the mouth; third, to form a flexible attachment between an artificial denture and a natural tooth and fourth, to construct the connection between an artificial denture and a natural tooth in such manner that the denture may have the necessary vertical, lateral, rocking, and angular movement with respect to the natural tooth that is desired to prevent stress being placed on the natural tooth and may have proper contact with the gum.

With these and other objects in view, one embodiment of my invention is shown in the accompanying drawings, in which:

Figure 1 is a perspective of a conventional representation of the gum of the lower jaw with an artificial denture on one side connected to the natural teeth and with the denture on the opposite side omitted;

Figure 2 is a perspective of a fragment of an artificial denture showing the location on a tooth on said denture of a part of the connecting means;

Figure 3 is a perspective of two parts of my connection shown separately and independently of a tooth and an artificial denture;

Figure 4 is a vertical section through my device and a part of the artificial denture;

Figure 5 is a section on line 5—5 of Figure 4;

Figure 6 is a perspective showing the clasp and a modified form of connection and

Figure 7 is a section similar to Figure 4 showing a modified form of connection and omitting the artificial denture.

In Figure 1 of the drawings there appears

a part of the representation of a conventional lower jaw and gums 1 such as are commonly used in illustrating the construction and use of artificial dentures. The jaw 60 shows natural teeth 2 and an artificial denture 3 having teeth 4 therein. One-half of the artificial denture having a lingual bar 5 to be used to connect the two parts of the denture together when the denture is complete is illustrated; one-half being omitted to show the construction and position of the connection. The part of the denture omitted from Figure 1 is indicated fragmentary in Figure 2. 70 Attached to a clasp 6 comprising the usual band 7 and a cusp 8, if a cusp be desired, is a plate 9. This plate may be attached in any desired manner as by soldering or casting. This plate is flat, relatively thin and 75 rectangular in shape and has at the lower end thereof and integral therewith a hook 10 spaced from the plate and extending upward parallel with the face thereof. A rectangular, relatively thin, hollow member 11 80 having a slot 12 in one side thereof and with one end open until the two parts of the connection are joined, is soldered, cast, or otherwise attached to a strip or plate of metal constituting a part of the artificial denture. 85 The parts of the connection are attached together to be used by sliding the hollow member over the hook and then bending up at a right angle to the plane of the hollow member and part 14 of said hollow member, 90 as indicated in Figures 4 and 7.

In the form of connection shown in Figures 6 and 7 the hook and the plate form a hinge. This hook 15 instead of being an integral part of the plate is attached thereto 95 to form a hinge. The hinge is constructed by forming at the bottom of the plate 9 an extension curved to adapt it to be inserted in two openings 17 in the hook. The hook, therefore, swings on an axis 18 made by 100 the narrow piece of metal between the two openings. The hook may be attached to or removed from the plate due to the opening between the end of the curved extension and the part from which it extends.

The construction and manner of using my device will be apparent from the description given and the drawings referred to. The clasp part may be properly fitted to the tooth and the plate may then be attached thereto in the desired position. The artificial denture may be fitted to the gum and

the attaching member may be properly adjusted. The two parts when completed may then be joined by inserting the hook into the hollow rectangular member and then closing 5 the opening in the rectangular member by bending up the extension of one of the sides thereof as indicated.

Having described my invention what I 10 claim as new and desire to protect by Letters Patent is:

1. An attachment for artificial dentures comprising a plate attached to means removably connected with a natural tooth and having an upturned hook at one end of said 15 plate and a hollow member attached to a denture body and adapted to form a movable connection with said hook.

2. An attachment for artificial dentures comprising a plate attached to means removably connected with a natural tooth and having a hook at one end of said plate, said hook spaced away from said plate and extending upward parallel with the face of 20 said plate and a hollow member having a slot in one side thereof attached to a denture body and adapted to form a movable connection with said hook.

3. An attachment for artificial dentures comprising a plate attached to means removably connected with a natural tooth and having a hinged hook at one end of said 30 plate, said hook spaced away from said plate and extending upward parallel with the face of said plate and a hollow member having a slot in one side thereof attached to a denture body and adapted to form a connection with said hinged hook.

4. In an artificial denture a denture body and means to attach said body to a natural 40 tooth comprising a clasp having a hinged hook attached thereto, whereby said hook may be moved angularly with respect to the face of said clasp, said denture body having a slotted hollow member attached thereto, said hook being adapted to form a sliding connection with said hollow member and means to fasten said hook and member together.

5. In an artificial denture a denture body and means to attach said body to a natural 50 tooth comprising a clasp on said tooth, said clasp having a hinged hook attached thereto,

said hook having the point thereof of greater diameter than the shank thereof, said point being substantially rectangular and having the corners rounded whereby rocking movement between the clasp and the denture is formed, said denture body having a slotted hollow member attached thereto, said hook being adapted to form a sliding connection with said hollow member and means to fasten said hook and said hollow member together.

6. A device of the character described, 60 consisting of means to connect an artificial denture to a natural tooth, said means comprising a removable member on said tooth, a hook attached to said member, said hook spaced away from and extending upward from the bottom of said member, said hook having a narrow shank and enlarged head, said head being substantially rectangular and having the corners rounded, a slotted hollow member attached to said artificial denture adapted to receive said hook therein to form a slideable and rotatable connection between said denture and said tooth and means to fasten said hook and said hollow member together.

7. A device of the character described, 70 consisting of means to connect an artificial denture to a natural tooth, said means comprising a removable member on said tooth, a hinged hook attached to said member, said hinged hook spaced away from and extending upward from the bottom of said member, said hinged hook having a narrow shank and enlarged head, said head being substantially rectangular and having the corners rounded, a slotted hollow member attached to said artificial denture adapted to receive said hinged hook therein to form a slideable and rotatable connection between said denture and said tooth and means to fasten said hinged hook and said hollow member together.

8. An attachment for an artificial denture comprising a hollow slotted member and hinged hook member secured to said slotted member.

In testimony whereof I affix my signature.

AUGUSTUS S. VAN HOUTEN.
